UNITED STATES PATENT OFFICE.

CLARENCE B. HILL, OF MANNINGTON, WEST VIRGINIA.

DEVICE FOR PREVENTING MICE ENTERING PIANOS.

1,011,344.

Specification of Letters Patent.

Patented Dec. 12, 1911.

Application filed July 17, 1911. Serial No. 638,965.

To all whom it may concern:

Be it known that I, CLARENCE B. HILL, a citizen of the United States, residing at 5
Mannington, in the county of Marion and
State of West Virginia, have invented cer-
tain new and useful Improvements in De-
vices for Preventing Mice Entering Pianos;
and I do hereby declare the following to
be a full, clear, and exact description of the
invention, such as will enable others skilled
in the art to which it appertains to make
and use the same, reference being had to
the accompanying drawings, and to the let-
ters and figures of reference marked there-
on, which form a part of this specification.

This invention relates to new and useful
improvements in devices for preventing
mice from entering pianos and other objects
and consists essentially in the provision of
20 an adjustable attachment to the pedal so
arranged as to make it difficult for the
mouse to run up pedals to the instrument.

The invention comprises various details
of construction and combinations and ar-
rangements of parts which will be herein-
after fully described and then specifically
defined in the appended claim.

I illustrate my invention in the accom-
panying drawings, in which:—
30 Figure 1 is a perspective view showing
the application of the device to the pedal
of a piano. Fig. 2 is an enlarged detail per-
spective view of the device removed, and
Fig. 3 is a sectional view.

35 Reference now being had to the details
of the drawings by letter, A designates a
band adapted to surround the pedal of a
piano and provided with apertures B

through which a screw or bolt D passes and
affording means whereby the device may 40
be clamped securely in place.

E designates a plate which may be of
any shape and size and has fastened there-
to the angled end of a strip F which has a
strap H secured at its ends to the face there-
of and affording means whereby the band 45
may pass between said strap and the face
of the plate, the latter being held in ad-
justed position by means of friction.

By the provision of a device of the nature 50
shown, it will be noted that a simple and
efficient means is afforded whereby mice
may be prevented from entering a piano,
thereby avoiding the destruction to prop-
erty which is a common fault where pianos 55
are not provided with means to protect the
same.

What I claim to be new is:—

A device for preventing mice from en-
tering pianos, comprising a band for attach-
ment to the pedal of a piano, a plate 60
positioned underneath the pedal having its up-
per edge conforming to the contour of the
under portion of the pedal, the plate adapt-
ed to normally close the pedal opening in 65
the foot board of the piano, an angled bar
fastened to said plate, a strap fastened to
the bar and spaced apart from the latter
to provide a passage within which the band
is passed and held by frictional contact. 70

In testimony whereof I hereunto affix my
signature in the presence of two witnesses.

CLARENCE B. HILL.

Witnesses:

L. N. BEATY,
C. L. PRICHARD.
